UNITED STATES PATENT OFFICE.

CHARLES D. RANDEL, OF NEW YORK, N. Y., ASSIGNOR OF ONE-HALF TO
WASHINGTON BROCKNER, OF SAME PLACE.

WIRE-BENDING MACHINE FOR BALE-TIES.

SPECIFICATION forming part of Letters Patent No. 271,514, dated January 30, 1883.
Application filed June 8, 1882. (No model.)

To all whom it may concern:

Be it known that I, CHARLES D. RANDEL, a citizen of the United States, residing at New York, in the county and State of New York, have invented new and useful Improvements 5 in Wire-Bending Machines for Bale-Ties, of which the following is a specification.

The object of this invention is to bend a loop upon the end of a wire and twist the wire together to form one end of a bale-tie or similar article.

In the accompanying drawings, Figure 1 represents a longitudinal vertical section of a machine constructed in accordance with my 15 invention; Fig. 2, a transverse vertical section on the line $x-x$ of Fig. 1, looking in the direction of the arrow 1; Fig. 2*, a view of the upper portion of Fig. 2, showing the clamp raised; Fig. 3, a transverse section on the line $x-x$ of 20 Fig. 1, looking in the direction of the arrow 2; Fig. 4, a plan or top view of Fig. 1; Fig. 5, a transverse sectional view on the line $y-y$ of Fig. 1; Fig. 6, a side elevation of the machine.

Similar letters indicate corresponding parts. 25 In these drawings, the letter A designates the frame or bed of my machine, which rests upon legs B, and is constructed similar to the bed of a turning-lathe. The ends of this bed form the bearings for the actuating-shaft C, 30 to which a revolving motion is imparted by hand or by any other suitable power.

On the bed A are secured two head-stocks, D E, the head-stock D being cast solid with or otherwise firmly connected to the bed, while 35 the head-stock E is adjustably connected to the bed, so that it can be placed at a greater or smaller distance from the fixed head-stock.

In the fixed head-stock is mounted a spindle, F, and on the rear end of this spindle is firmly 40 secured a pinion, a, which gears into a segmental cog-wheel, b, formed on a portion of the circumference of a disk, I, which is mounted on the actuating-shaft C, so that by turning this shaft an intermittent revolving motion is imparted to the spindle F. On the 45 front end of this spindle is firmly mounted a head, G, which carries the mechanism for bending and for twisting the wire. This head is provided with an abutting shoulder, c, and 50 with an arm, d, and on the surface of this arm is firmly secured a bracket, e, provided with a groove for the reception of the wire.

Above this bracket is a lug, f, formed to correspond to the shape of the loop to be produced on the wire, and situated at such a distance from the bracket that just room enough 55 is left between the two for the introduction of the wire.

Between the bracket e and the abutting shoulder c is situated the bending-arm g. This 60 arm is mounted on a pivot, h, Fig. 4, which is secured in a shoe, h*, fitted to the outside of the arm d, and which extends through a cam-shaped slot, i, in said arm.

From the shoe h* extends a pin, j, into a 65 slot, k, formed in a bracket, k*, which rises from a slide, l, fitted into guide-slots m in the stationary head-stock D.

On the outer end of the slide l is secured a roller-stud, n, and the slide l is pushed forward, 70 and as the motion of the actuating-shaft progresses the stud n engages with a cam-groove, p, in the cam H, and the slide l is carried back, thus imparting a positive motion to the bending-arm in either direction. This forward-and-backward motion of the slide takes place during the time the spindle F remains stationary, 75 and as the said slide moves forward the pivot h* of the bending-arm g moves up in the cam-shaped slot i, and the bending-arm g is caused 80 to move over the lug f. When the bending-arm is in its normal position its upper surface is level with the surface of the bracket e, and in said upper surface of the bending-arm is formed a groove corresponding to the groove 85 in the bracket. The wire which rests upon the bracket and upon the bending-arm, and the end of which abuts against the shoulder c, is bent over the lug f by the motion of the bending-arm, as shown in Fig. 6, and the bent end 90 of the wire is caught beneath a finger, q, which will be presently described. When the wire has been bent the slide l moves back and the bending arm reassumes its normal position. The bending-arm g and the lug f, together 95 with suitable mechanism for moving the bending-arm, compose the loop-forming mechanism.

The finger q is formed on a lever, r, which is secured to a block, r*, fastened to the upper 100 surface of the movable head-stock E by a pivot, s, and the outer end of which extends into a lever, t, Fig. 2, which has its fulcrum on a pin, u, secured in the movable head-stock E, and

- the lower end of which is held in contact with a cam, a' , by means of a spring, b' , Fig. 1. The cam a' is mounted on the actuating-shaft C, and when its low portion is opposite to the end of the lever t the finger q is drawn back; but if the high part of said cam acts upon the lever t the finger q is pushed forward so as to project over the groove c' in the movable head-stock, through which the wire is introduced.
- 10 This groove c' is formed between the inner edge of the block r^* and a jaw, d' , which is fitted into a cavity in the movable head-stock, Fig. 1, and the stem e' of which is depressed by the action of a spring, f' , upon the surface of a cam, g' , mounted on the actuating-shaft C. When the bending-arm g has reached the position shown in Fig. 6, the jaw d' is raised and the finger q is pressed forward, and by these means the bent end of the wire is held between the block r^* and the jaw d' . The bending-arm g is then carried back to its normal position by the action of the cam-groove p on the roller-stud l , and immediately thereafter the segmental cog-wheel b engages with the pinion a , and a rapid revolving motion is imparted to the spindle F, and since the wire has been bent over the lug f its ends, which are retained between the jaw d' and block r^* , are twisted together by the revolving motion of the spindle F and its head G. In the face of the abutment r^* is a recess, q^2 , and after the inner end of the wire has been bent, as shown in Fig. 6, both ends or strands lie between the clamp d' and abutment r^* , as shown in Fig. 2, and when the clamp rises the lip q retains the wires in the position shown in Fig. 2*, so that they are twisted together when the mandrel revolves. As soon as the segmental cog-wheel b releases the pinion a a lever-pawl, h' , drops into a notch, i' , Fig. 4, formed in the circumference of a disk, j' , which is mounted on the spindle F, the motion of this spindle is arrested, and the spindle is retained in the position shown in Fig. 1. At the same time the jaw d drops and the finger q recedes immediately after the spindle has come to its position of rest, the ejector k' is actuated, and the loop of the wire is thrown off from the lug f .
- 50 The lever-pawl h' has its fulcrum on a pivot, l' , secured in a stud projecting from the inner end of the stationary head-stock D, and it is guided in a forked stud, m' , rising from the outer end of said head-stock.
- 55 To the side of the lever-pawl is secured a rod, n' , which is depressed by the action of a spring, o' , upon a cam, p' , mounted on the actuating-shaft C, Fig. 3. When the high portion of this cam comes beneath the rod n' the lever-pawl h' is raised out of gear with the disk j' and the spindle F is free to be revolved; but as long as the low portion of the cam p' is beneath the rod n' the lever-pawl h' is depressed, and it drops into the notch of the disk j' as soon as this notch comes beneath it, thereby retaining the spindle in its position of rest.

The ejector k' , Fig. 2, consists of a lever mounted on a pivot, l^2 , which is secured in a bracket, k^3 , fastened to the bed A. A spring, k^4 , draws the ejector back to the position shown in Fig. 2.

From the actuating-shaft projects a pin, k^5 , which at the proper moment strikes the lower end of the ejector-lever and serves to actuate the ejector in the desired manner.

What I claim as new, and desire to secure by Letters Patent, is—

1. The combination, substantially as herein-before described, of the intermittently-rotating spindle F, the head carried by the same, the lug f and bracket e on the head, the bending-arm g , movable on said head, and means for advancing and raising the bending-arm over said lug to bend the wire around the latter, substantially as described.

2. The combination, substantially as herein-before set forth, of the spindle F, the head formed on said spindle, the wire-supporting bracket on said head, the loop-forming mechanism, the head-block E, the block r^* , the movable jaw d' , the wire-retaining finger q , and means for operating the loop-forming mechanism and the movable jaw.

3. The combination, substantially as herein-before described, of the spindle F, the head formed on said spindle, the wire-supporting bracket on the head, the loop-forming mechanism, the head-block E, the block r^* , the movable jaw d' , the wire-retaining finger q , and means for intermittently rotating the spindle and operating the loop-forming mechanism and the movable jaw.

4. The combination, substantially as herein-before described, of the spindle F, the head formed on said spindle, the wire-retaining bracket on the head, the loop-forming mechanism, the head-block E, the block r^* , the movable jaw d' , the wire-retaining finger q , the ejector, and means for rotating the spindle and operating the loop-forming mechanism, the movable jaw, and the ejector.

5. The combination, substantially as herein-before described, of the spindle F, the head formed on said spindle, the wire-supporting bracket on said head, the loop-forming mechanism, and the lever-pawl for retaining the spindle in position while the loop-forming mechanism is in motion.

6. The combination, substantially as herein-before described, of the spindle F, the head formed on said spindle, the wire supporting bracket on said head, the lug f , the bending-arm g , the cam-slot i , and the cam H for imparting a positive motion to the bending-arm in either direction.

In testimony whereof I have hereunto set my hand and seal in the presence of two subscribing witnesses.
